yarn receivers, operating mechanism for the builder mechanism having provision for suspending operation of the builder mechanism and cause the yarn to be wound on the yarn 5 receivers without traversing longitudinally thereof, means operable during the winding of the yarn without traverse to automatically start the builder mechanism in operation after a predetermined number of windings 10 have been wound on the yarn receiver, and a single manually controlled means operable to suspend operation of the builder mechanism and to start operation of the means that controls the starting of the builder 15 mechanism.

4. In a machine of the class described, the combination of yarn receivers, yarn guiding means for directing yarn to the yarn receivers during their rotation, a builder arm, 20 connections between the builder arm and yarn guiding means, a builder cam, means for rotating the builder cam to effect traverse of the yarn guiding means, and means for suspending the rotation of the builder cam during 25 the rotation of the yarn receivers to wind a reserve supply of yarn upon the yarn receivers without traverse and for automatically resuming rotation of the builder cam when the reserve supply of yarn has been 30 wound upon the receivers.

5. In a traverse mechanism for winding yarn upon yarn receivers, the combination of rotating yarn receivers, yarn guiding means for directing yarn to the yarn receivers, a 35 builder arm, connections between the builder arm and yarn guiding means, a builder cam, means for operating the builder cam to cause the builder arm to traverse the yarn guiding means, means for disconnecting the builder 40 cam from its operating means to cause windings of yarn to be wound on the yarn receivers without traverse and for automatically connecting the builder cam to its operating means to cause windings of yarn to 45 be wound upon the yarn receivers with traverse after a plurality of windings have been wound on the receivers without traverse.

6. In a transverse mechanism for winding 50 yarn upon yarn receivers, the combination of rotating yarn receivers, yarn guiding means for directing yarn to the yarn receivers, a builder mechanism for traversing the yarn guiding means longitudinally of 55 the yarn receivers, operating means for the building mechanism having provision for suspending the operation of the builder mechanism and causing the yarn to be wound on one end of the yarn receivers without 60 traverse longitudinally thereof, automatic means for starting the builder mechanism in operation after a plurality of windings have been wound on the yarn receivers without traverse, and a single manually controlled 65 means operable to suspend operation of the

builder mechanism and to set said automatic means in operation.

7. In a machine of the class described, the combination of yarn receivers, a yarn guide rail for directing yarn to the rotating yarn 70 receivers, a builder arm connected to the yarn guide rail, a builder cam engaged by and for operating the builder arm, means for operating the builder cam, means for disconnecting the builder cam from its operating means and permitting the builder arm to turn the builder cam to starting position, and automatic means for connecting the builder cam to its operating means to effect winding a reserve supply of yarn on the 75 yarn receivers without traverse and to start the winding with traverse at the base of the yarn receivers.

8. In a machine of the class described, the combination of yarn receivers, yarn guiding 80 means for directing yarn to the yarn receivers, traversing mechanism for traversing the yarn guiding means longitudinally of the yarn receivers, and means for suspending the operation of the traversing mechanism and movement of the guiding means longitudinally of the yarn receiver to cause yarn to be wound on the receivers without traverse and for causing the operation of the traversing mechanism to be commenced at 85 the base of the yarn receivers after a plurality of windings have been laid on the receivers without traverse and to place traverse windings over said plurality of windings.

9. In a machine of the class described, the 90 combination of a ring-rail, a builder arm, connections between the builder arm and ring-rail, a builder cam, means for operating the builder cam, means for throwing the builder cam operating means out of operative relation with the builder cam, a latch for holding the builder cam operating means out of operative position, and means for tripping the latch to permit the operating 95 means to become effective.

10. In a machine of the class described, the combination of a ring-rail, a builder cam, a builder arm bearing against the builder cam, connections between the builder arm and ring-rail, a continuously operating 100 shaft for operating the builder cam, and means for disconnecting the said shaft from operative connection with the builder cam for interrupting the traverse of the ring-rail 105 and causing the builder arm to turn the builder cam to its initial or starting position.

11. In a machine of the class described, the combination of a ring-rail, a builder cam, a builder arm, connections between the 110 builder arm and ring-rail, a shaft for operating the builder cam, means for disconnecting the shaft from the builder cam, a latch for holding the shaft and builder cam in 115 relatively inoperative relation, and means 120

125 relatively inoperative relation, and means 130

for automatically tripping the latch to permit the shaft to resume operative relation with the builder cam.

12. In a machine of the class described, 5 the combination of yarn receivers, a ring-rail, a builder cam, a builder arm bearing upon the builder cam, connections between the builder arm and ring-rail, means for operating the builder cam, manually controlled means for disconnecting the builder cam and its operating means to cause yarn to be laid upon the yarn receivers without traverse, a latch for holding the builder cam and its operating means in inoperative relation, and automatic means for tripping the 15 latch to permit the builder cam and its operating means to become operatively related.

13. In a machine of the class described, 20 the combination of yarn receivers, a ring-rail, a builder cam, a builder arm bearing upon the builder cam, connections between the builder arm and ring-rail, means for operating the builder cam, manually controlled means for disconnecting the builder cam and its operating means to cause yarn to be laid upon the yarn receivers without 25 traverse, a latch for holding the builder cam and its operating means in inoperative relation, automatic means for tripping the 30 latch to permit the cam and its operating means to become operatively related, and means for predetermining the number of

windings to be laid upon the yarn receivers without traverse.

14. In a machine of the class described, 35 the combination of yarn receivers, a ring-rail, a builder cam, connections between the builder cam and ring-rail, a builder cam operating shaft, connections between said shaft and the builder cam for operating the 40 latter from the former, means for operatively disconnecting the builder cam and its operating shaft, and automatic means for thereafter connecting the builder cam and its operating shaft. 45

15. In a machine of the class described, the combination of yarn receivers, a yarn guide rail for directing yarn to the rotating yarn receivers, a builder arm connected to the yarn guide rail, a builder cam, means for 50 operating the builder cam, means for disconnecting the builder cam and its operating means at the time of doffing and permit the builder arm to turn the builder cam to starting position that a bunch may be built adjacent the head of the yarn receivers without traverse on commencement of the winding operation and means for automatically connecting the builder cam with its operating means at the conclusion of the bunch 55 to continue the winding with traverse.

In testimony whereof, I have signed my name to this specification.

HARRY A. LEONARD.

UNITED STATES PATENT OFFICE.

HARRY A. LEONARD, OF HOPEDALE, MASSACHUSETTS, ASSIGNOR TO DRAPER CORPORATION, OF HOPEDALE, MASSACHUSETTS, A CORPORATION OF MAINE.

SPINNING OR WINDING MACHINE.

1,412,808.

Specification of Letters Patent. Patented Apr. 11, 1922.

Application filed January 17, 1921. Serial No. 437,749.

To all whom it may concern:

Be it known that I, HARRY A. LEONARD, a citizen of the United States, residing at Hopedale, in the county of Worcester and State of Massachusetts, have invented an Improvement in Spinning or Winding Machines, of which the following description, in connection with the accompanying drawings, is a specification, like characters on the drawings representing like parts.

This invention relates to machines for winding yarn on yarn receivers, and more particularly to machines for winding the yarn on the yarn receivers for use as weft or filling in "feeler looms."

In one type of "feeler looms" now extensively used, it is the usual practice to replenish the filling prior to complete exhaustion of that in the running shuttle. This replenishment may be effected either by substituting for the shuttle in play another having a supply of filling in it, or by ejecting the yarn receiver or carrier in the shuttle and substituting another having a working supply of yarn or filling thereon.

In order that perfect cloth may be woven, it is necessary that the final pick prior to replenishment shall be a "full pick", that is, that a full length of filling or weft thread shall be laid throughout the width of the shed; and to effect this it has been usual heretofore to cause the feeler mechanism to call the change and effect replenishment when there still remained upon the yarn receiver or carrier a greater length of filling than necessary to provide a full final pick and tension on the final pick laid in the shed. Any surplus yarn or filling remaining on the ejected yarn receiver or carrier constitutes waste, and economy in the production of cloth dictates that such waste be as small as possible, consistent with the desired results.

In some types of feeler looms, it has been suggested to provide the yarn receivers or carriers with a "bunch" of yarn or filling, and to have cooperate therewith the feeler mechanism to effect a change of filling when the bunch has been reached. The bunch, however, usually contains more filling than is necessary to lay a final full pick, and moreover, difficulty is experienced in providing filling carriers or receivers with a bunch properly located and of proper amount. In forming the bunch it is the

practice to traverse the yarn or filling longitudinally of the yarn receivers or filling carriers and to then pass to the full service traverse after the bunch is completed. This expedient is liable to cause the "ends" (that is, the yarn) to be broken, and is otherwise objectionable.

An important feature of the present invention, therefore, consists of means for providing the yarn receivers or filling carriers with a reserve supply of filling sufficient in amount to insure a final perfect pick prior to the change of filling, and to wind the reserve supply upon the filling carriers or receivers without traverse and then to resume the traverse when the reserve supply has been wound.

A further important feature of the invention consists in means for rendering the traversing mechanism ineffectual during the winding of the reserve supply of filling on the yarn receivers or carriers and to bring the traversing mechanism automatically into action when such reserve supply has been wound.

The amount of reserve supply that is wound upon the filling carriers without traverse should vary under certain conditions, and another important feature of the present invention, therefore, consists in means for predetermining the number of windings that shall be wound upon the filling carriers or receivers to constitute the reserve supply without the traverse.

When the traversing mechanism is brought into action to lay the yarn upon the yarn receivers or carriers with a traverse longitudinally thereof, it is desirable that the winding of the yarn upon the yarn receivers or carriers be commenced at the base of the filling carriers or receivers; and another important feature of the invention, therefore, consists of means which insure commencement of the traverse windings at the base of the filling carriers or receivers after the reserve supply wound without the traverse has been completed.

Other features of the invention and novel combination of parts will be hereinafter described in addition to the above, and in connection with the accompanying drawings which illustrate a good, practical form of the invention.

In the drawings:

Figure 1 is a front elevation of a portion

of a machine for winding yarn upon yarn receivers, showing the present invention associated therewith;

Fig. 2 is a side elevation of a yarn receiver 5 or bobbin showing the reserve supply of filling wound upon the yarn receiver without traverse near the base thereof;

Fig. 3 is a perspective view with certain 10 of the machine and the association of the present invention therewith;

Fig. 4 is a detached detail, some of the parts being shown in section, illustrating the pick-wheel and associated elements;

Fig. 5 is a side elevation, parts being 15 broken away, showing more particularly the relation of parts when the traverse mechanism is in operation;

Fig. 6 is a top or plan view of the parts 20 shown by Fig. 5; and

Fig. 7 is a detached detail on an enlarged scale, showing the trip slide and release.

In the drawings the invention is illustrated as embodied in a spinning and winding machine of the Howard and Bullough type, and while the invention has especial advantages in this connection it is to be understood that it is not confined thereto, but may be used advantageously with other 25 forms of spinning or winding machines.

The machine frame 1, which may be of usual construction, has extending longitudinally thereof between the end frames, the spindle supporting rail 2, and the tie rail 3, Fig. 1. The spindle rail 2 is adapted 30 to support one or more spindles for rotating the yarn receivers or bobbins 4, on which the yarn is to be wound. As the yarn is wound upon the yarn receivers or bobbins 35 4, it is directed thereto by the yarn guiding means which, in the present instance, consists of a ring-rail 5 carrying one or more rings 6 on which are the travellers 7, through which the yarn passes from a source 40 of supply to the yarn receivers or bobbins 4.

When the yarn receivers or bobbins are 45 to be supplied with yarn to be used as the filling or weft in the loom, the yarn is given a traversing movement longitudinally of the receivers or bobbins of a predetermined amount, and the path of such traversing movement is gradually changed from near the base toward the tip end of the yarn receivers or bobbins, in order that the yarn 50 may be laid upon the yarn receivers or bobbins by a "filling wind."

Depending from the yarn guiding means or ring-rail 5 are the lifter rods 8, of which there may be one or more, the lower end 55 60 whereof rests upon a roll or stud 9 carried by an arm 10 mounted at 11 on a bracket 12 supported by the machine frame, Fig. 1. Since the weight of the yarn guiding means or ring-rail 5 is considerable, it is usual to 65 counterbalance the arm 11 by weights (not

shown) mounted on a counterbalancing arm 13; but since such counterbalancing feature is old and well known, its further illustration is not deemed necessary.

Mounted on the shaft 11 in fixed relation 70 to the arm 10 is the arm 14, to which is connected at 15, the traversing mechanism. The parts thus far described are of usual construction.

Pivottally mounted on the machine frame 75 at 16 is the builder arm 17, and pivotally connected to the builder arm 17 at 18 (Figs. 1 and 3) is the auxiliary builder arm 19 which, in effect, forms part of the builder arm 17. There is an adjusting screw 20 80 between the arms 17 and 19.

The arm 19, which as above described, constitutes part of the builder arm, is provided with a roll 21 which bears upon a builder cam 22, the construction being such 85 that as the builder cam rotates, its peripheral cam surface 23 will cause the builder arm to oscillate upon its pivotal support 16. The roll 21 carried by the builder arm, is held in contact with the builder cam by 90 means of the weight of the ring rail and connected parts.

Mounted for rotative movement on the builder arm is the builder screw 26, Figs. 95 1 and 3, upon which is the travelling threaded head or nut 27. A flexible connection or chain 28 is secured to the head or nut 27 and passes over a roll 29, Figs. 1 and 3, from which it leads to a link 30 secured to the arm 14 by adjustable connection 15 100 hereinbefore referred to.

From the construction thus far described, it will be apparent that upon rotative movement of the builder cam 22, the builder arm will be oscillated on its support, and through 105 the chain 28 and connections, will cause traversing movement to the ring-rail or yarn guiding means 5.

In order that the traversing movement 110 imparted to the ring-rail may be shifted longitudinally of the yarn receivers or carriers, or given a "gain" toward the end of the yarn receivers or carriers, the builder screw 26 is given a rotative movement 115 through means that will now be described.

The builder screw 26 has secured to its lower end the bevel gear 31, Figs. 1 and 4, which meshes with a bevel gear 32 carried by the shaft 33, Fig. 4, which is rotatably mounted in the bearing 34. The shaft 33 120 has mounted thereon the pick wheel 35, Figs. 3 and 4, which is connected to the shaft 33 to rotate therewith. The bearing 34, Fig. 4, is extended to form a bearing for a sleeve 36, to which is fixed the chain wheel 37. The 125 sleeve 36 has the disc 38 secured thereto and carries the working pawl 39, best shown in Fig. 1. The pick wheel 35 has associated therewith the stop pawl 40, Fig. 1, the construction being such that when the pick 130

wheel 35 is rotated by the actuating pawl 39 from the sleeve 36, the holding pawl 40 will prevent retrograde movement of the pick wheel.

5 The chain wheel 37, Figs. 1 and 4, has secured thereto one end of a chain or flexible member 41, which passes around a guide wheel 42 mounted on the machine frame at 43, Fig. 1, and thence the chain passes downwardly about a roll 44 mounted on the part 19 of the builder arm, and the end chain is connected at a fixed point 45 which, in the present instance, is the front bearing of the cam shaft 46. From the construction described, it will be apparent that upon actuation of the builder cam, the builder arm will be oscillated and through the mechanism described, the builder screw 26 will be rotated to vary the path of travel of the 10 yarn guide or ring-rail 5, and the yarn will be laid upon the yarn receivers or bobbins with a traversing movement which gradually approaches the tip end portion of the receivers or bobbins, or in other words, with 15 a "filling wind."

The present invention contemplates that the yarn receivers or bobbins shall have wound upon them a reserve supply of yarn without traverse of the yarn longitudinally 20 of the yarn receivers or bobbins, and that the traverse mechanism shall then be rendered effective to continue the winding of the yarn upon the yarn receivers or bobbins with a traverse longitudinally of the yarn 25 receivers or bobbins.

The builder cam 22 is mounted upon the cam shaft 46, Figs. 1 and 3, and has depressions 47, of which there may be one or more, three being shown in the drawings. These 30 depressions 47, when engaged by the roll 21 of the builder arm, and when the screw head or nut 27 is in its upper position, Fig. 3, indicate that the yarn guiding means or ring-rail is at its lowest position.

45 Secured to the cam shaft 46 is the worm wheel 48, Figs. 3 and 5, through which a train of mechanism operates to actuate the builder cam.

Rotatably mounted in the sleeves 49 and 50 is the operating shaft 51, Figs. 3, 5 and 6. The bearing 50 is mounted on the brackets 52 for rocking movement about the pivotal connection 53. The bearing 49 is carried by the arms 54 which are secured to the shaft 55, Figs. 5 and 6. The arms 54 are preferably connected to the bearing 49 by means of the rod 56, which is extended to one side of the bearing 49 and there connected as at 57, Fig. 6, to a weight carrying arm 58 which is itself 60 loosely mounted upon the shaft 55 as shown in Figs. 5 and 6, and is provided with a stop 61 which limits the clockwise movement of the arms 54 about the supporting shaft 55. As a further means for supporting the weight 65 60 when it is in its lowered position, as indi-

cated in Fig. 5, a buffer pin 62 is mounted on a bracket 63 and rests upon a spring 64, the tension of which may be adjusted as desired, by a set screw 65.

Secured to the shaft 51 is the worm 66 which is adapted to be engaged with and disengaged from the cam operating worm wheel 48, the construction being such that when the weight 60 is in its lowered position as indicated in Fig. 5, the shaft 51 will be lowered 70 to cause the worm 66 to be engaged with the worm wheel 48; but should the weight 60 be lifted, the bearing 49 carrying one end of the shaft 51 will likewise be lifted through the arms 54, and the worm 66 will be disengaged 75 from the cam operating worm wheel 48 and the cam will be freed from its operating means. Under the conditions last stated, that is, when the cam 22 is not being operated, the yarn guide or ring-rail will not be traversed 80 longitudinally of the yarn receivers or carriers, and consequently any yarn wound upon the yarn receivers or carriers at such time will be wound thereon without traverse. Inasmuch, also, as the roll 21 of the builder arm 85 rests against the builder cam 22, when the builder cam 22 is freed from its operating means it will be caused to rotate to place the roll 21 in one of the depressions 47 of the builder cam, with the result that yarn wound 90 upon the yarn receivers or carriers without traverse, as described, will be wound upon the yarn receivers or carriers at the base portions thereof.

The shaft 55, Fig. 3, is extended laterally, 100 and has its end portion 67 supported in a bearing in the machine frame, Figs. 1 and 3. Secured to the shaft 55 is the hub portion 68 of an operating arm 69 which is preferably formed integral with the hub, as indicated in 105 Fig. 3. The hub 68 may be secured to the shaft 55 by any appropriate means such as the set screws 70. The operating arm 69 has a foot-piece 71, Fig. 1, adapted to be engaged by the foot of the workman for rotating the 110 shaft 55 under manual control, the construction being such that should the attendant depress the foot-piece 71, the shaft 55 will be rocked, thereby lifting the weight-carrying arm 58 and disengaging the worm 66 from 115 the worm wheel 48.

After a sufficient reserve supply of yarn has been wound upon the yarn receivers or bobbins without traverse, as above explained, it is desirable that the main windings placed 120 upon the yarn receivers or carriers be started with the desired filling wind traverse, and to this end the present invention provides automatic means for engaging the builder cam with its operating means after the reserve 125 supply of yarn has been wound upon the yarn receivers or carriers.

The shaft 51 may be rotated from any suitable source of power, and as shown in the present instance of the invention, the shaft 130

51 has a sprocket wheel 72 about which passes a sprocket chain 73, and by which the shaft 51 is rotated.

Mounted for rocking movement about the 5 supporting rod or shaft 74, Figs. 1, 3 and 5, is the latch 75, the upper portion 76 of which is adjustably connected to the lower portion by a slot and bolt adjusting means 77. The latch 75 has a weight supporting 10 shoulder 78 which, when the weight 60 is raised as hereinbefore explained, is carried beneath the weight 60 by means such as the weighted arm 79 of the latch. The weighted arm 79 provides a convenient form of means 15 for throwing the latch into the weight-supporting position, as indicated in Fig. 3, but it will be understood that any equivalent means such as a spring for instance, might be employed instead of the weight 79. The bracket 20 63 hereinbefore described, may be conveniently secured to the latch 75, as indicated in Fig. 5, by the adjusting bolt 80.

When the weight 60 is engaged with the shoulder 78 and the reserve supply of yarn 25 is being wound upon the yarn receivers or carriers without traverse, it is desirable to trip the latch automatically and free the weight to cause the builder cam operating mechanism again to become effective. To 30 this end the upper portion 76 of the latch has adjustably secured at its upper end the trip 81. Adjustment of the trip 81 with relation to the arm 76 may be variously effected, but in the present instance of the invention the 35 trip 81 is provided with a slot 82 through which passes the securing bolt 83, Figs. 1 and 7.

Secured in the brackets 84, mounted on the machine frame adjacent the shaft 51 are the 40 guide rods 86 on which is mounted the trip slide or carriage 87, the lower face portion of which is provided with a series of teeth 88, Fig. 7. The trip slide 87 is normally under the influence of a spring 89, one end of which 45 is connected to the slide at 90, and the other to a fixed part as at 91, the construction being such that the slide 87 will normally be held in a position indicated in Figs. 3 and 7. A buffer spring 92 may be interposed between the slide 50 87 and the bracket 84 to absorb the shock when the slide is freed for the action of the spring 89 as will presently appear.

The cam operating shaft 51 has secured to it a second worm 93, Figs. 3, 5 and 6, which 55 is normally below the teeth 88 of the trip slide 87, but when the shaft 51 is moved upwardly to disengage the shaft 51 from the train of mechanism between it and the builder cam, it will be brought into engagement with the teeth 88 of the trip slide 87. Under the conditions stated, the trip slide 60 87 will be thereupon moved along the guide rods 86, since the shaft 51 continues in operation. The trip slide 87 carries a pin 94 65 which is adapted to engage the trip 81 when

the trip slide has been moved the predetermined extent. The trip 75 will be turned about its axial support 74, to the right, Fig. 5, or to the left, Fig. 1, by the pin 94, and the weight 60 will be released, thereupon 70 lowering the bearing 49 and bringing the worm 66 into operative engagement with the worm wheel 48 and starting the builder cam and traverse mechanism.

Since the trip 81 is adjustably secured to 75 the latch or upper member 76 of the latch, it follows that adjustment of the trip 81 will determine the number of windings that shall be made upon the yarn receiver or carrier to constitute the reserve supply of windings 80 without traverse; and when the latch has been tripped as hereinbefore described, to permit the weight 60 to drop, the worm 93 will be disengaged from the trip slide 87 and the latter will be moved to its initial position, Fig. 7, under the impulse of the spring 89.

What is claimed is:

1. In a machine of the class described, the combination of a series of yarn receivers, 90 guiding means for directing yarn to the receivers during their rotation, a traversing mechanism for imparting a traverse movement to the yarn guiding means longitudinally of the yarn receivers, means for suspending the operation of the traverse means during the rotation of the yarn receivers to wind yarn thereon without traverse, means for automatically re-instating the operation 95 of the traverse mechanism upon completion of the winding of yarn without traverse, and driving means for the traversing mechanism and the re-instating means movable alternately into operative engagement with each 100 of them.

2. In a machine of the class described, the combination of a series of yarn receivers, guiding means for directing yarn to the receivers during their rotation, a traversing mechanism for imparting a traverse movement to the yarn guiding means longitudinally of the yarn receivers, means for suspending the operation of the traverse means during the rotation of the yarn receivers to wind yarn thereon without traverse, means for automatically re-instating the operation 110 of the traverse mechanism upon completion of the winding of yarn without traverse, and driving means for the traversing mechanism and the re-instating means movable in one 115 direction to operatively engage the traversing mechanism and movable in the opposite direction to operatively engage the re-instating means.

3. In a traverse mechanism for winding 125 yarn upon yarn receivers, the combination of rotating yarn receivers, yarn guiding means for directing yarn to the yarn receivers, a builder mechanism for traversing the yarn guiding means longitudinally of the 130
